UNITED STATES PATENT OFFICE

2,551,987

GAS HAMMER STARTER

Carl S. Weyandt, Homer City, Pa.

Application December 9, 1946, Serial No. 714,985

1 Claim. (Cl. 123—7)

1

This invention relates generally to portable internal combustion percussion tools or portable gasoline hammers and more particularly to apparatus for starting tools of this character.

This invention is a continuation in part of application Serial No. 496,709, filed July 30, 1943, now Patent No. 2,433,007 granted December 23, 1947.

Gasoline hammers are self-contained two cycle gasoline engines. These tools carry their own fuel and develop their own power for drilling holes, breaking stone or concrete, stamping ties and other similar work. They are normally held in a substantially vertical position during operation and it is difficult to balance them with one hand while setting and winding a knotted starter rope around the notched starter pulley to spin the crankshaft. As with outboard motors, these two cycle engines may require two or more crankings before they start operating. An outboard motor attached to a boat does not present a difficult problem as both hands are free to set and wind the starter rope and hold the motor when the starter rope is pulled. However a gasoline hammer is held in a vertical position to start it and the left hand must be employed to steady and hold the hammer directly above the pull on the starter rope to prevent the hammer from turning and twisting out of the operator's grasp and falling to the ground, or to prevent the starter rope from fouling.

These problems are solved by the application of a recoil starter to a gasoline hammer, and the principal object of this invention is the provision of a recoil starter for a gasoline hammer to facilitate starting the same.

Another object is the provision of a recoil starter that permits the crankshaft of the gasoline hammer to be stepped around for charging the cylinder with fuel preparatory to applying the starting pull.

Another object is the provision of an internal combustion percussion hand tool having a guiding handle disposed in substantial vertical alignment with a pull cord starting mechanism which permits the tool to be steadied with one hand while the operator actuates the pull cord with the other hand and thus prevents the tool from being twisted from the grasp of the operator.

Another object is the provision of an internal combustion percussion tool having a timing piston and a working piston and arranged to be started by the operation of the timing piston.

Other objects and advantages appear in the following description and claim.

2

A practical embodiment illustrating the principles of this invention is shown in the accompanying drawings wherein:

Fig. 1 is a view in side elevation showing the recoil starter on the gasoline hammer.

Fig. 2 is a fragmentary front view of the gasoline hammer with the recoil starter shown in section.

Fig. 3 is an enlarged view in side elevation of the recoil starter with a portion of the cover and bracket broken away.

Fig. 4 is a top plan view of Fig. 3 with the cover removed.

Fig. 5 is a sectional view of the starter pulley and shaft taken along the line 5—5 of Fig. 4 with the pawl and pawl spring superimposed thereon.

Fig. 6 is a fragmentary sectional view of the gasoline hammer with the modified form of recoil starter.

Fig. 7 is an end view of the structure shown in Fig. 6 with parts broken away.

Fig. 8 is a longitudinal view in section taken on the line 8—8 of Fig. 1.

Referring first to Figs. 1 and 2 the gasoline hammer comprises the cylinder casting 10 in which a timing piston and a percussive working piston operate. The lower end of the cylinder 10 has the nose casting 11 secured thereto which is arranged to receive the bit or tool 12.

The upper end of the cylinder casting 10 has the split crankcase 13 bolted thereto which houses the crankshaft 14 rotatably supported in the antifriction bearings 15. The right end of the crankshaft in Fig. 2 carries the flywheel 16 and the left end has the recoil starter mechanism mounted thereon.

The timing piston 1 is connected to the crankshaft 14 by means of the connecting rod 3 shown in Fig. 8. The timing piston controls the combustion of fuel in the combustion chamber between the two pistons which drives the working piston 2 in a working direction to strike the bit 12. When the working piston uncovers the port 4 exhaust gas is conducted through the passage 5 and the valve 6 to the underside of the working piston where the pressure of the exhaust gas is effective in returning the working piston. The valve 6 is actuated by the rod 7 attached to the fuel throttle beam 8 which in turn is actuated

by the fuel throttle lever 59 on the handle 58. A lost motion connection 9 is provided between the rod 7 and the valve 6 to permit an additional supply of fuel to the engine before the valve 6 opens the passage 5.

The crank shaft 14 has the collar 17 and the

hubbed ratchet gear 18 pinned thereon in spaced relation as shown in Fig. 5. The bushed starter pulley 20 is journaled on the crankshaft between the collar 17 and the ratchet gear 18 and would be free to rotate thereon if it were not for the helical spring 21, one end of which is looped around the post 22 in the pulley 20 and the other end is secured by the set screw 23 in the frame 24 which encircles the lower half of the starting mechanism.

The pull cord or cable 25 is attached to the handle 26 at one end and wrapped around the groove 27 in the dished rim of the starter pulley 20. The pull cord makes one complete turn around the pulley and its other end is secured in the socket 28 which in turn is fastened to the pulley 20 as by the rivet 29 as shown in Fig. 3. The pull cord 25 is threaded between the grooved guide rollers 30 and 31 supported by the frame 24 on the inside and by the plate 32 on the outside with the bolts 33 and 34 providing the shafts on which the respective guide rollers 30 and 31 rotate.

The frame 24 has three bolt holes 35, 36 and 37 for securing it to the crank case 13. The bolt 33 and the bolts 38 and 39 secure the cover 40 which encloses the top of the recoil starting apparatus. The holes 41 and 42 in the frame 24 are in that portion of the wall that extends upwardly in front of the pulley and is indicated as 43 and is provided with an inwardly projecting arcuate cam surface 44, the inner edge of which is spaced from the ratchet gear 18 but lies slightly within the rim of the pulley 20.

The dished side of the starter pulley 20 is provided with a semi-cylindrical socket 45 arranged to receive the mating joint 46 of the ratchet 47. The ratchet is made up of a plurality of stamped parts. The surfaces of the socket 45 and the joint 46 are concentric to the pin 48 which extends through the wall of the pulley and is fastened by the pin 49 on one side and has a reduced portion on the other side that passes through a hole in the ratchet parts and is peened to hold them in assembled relation. A second pin 50 also has a reduced portion extending through the ratchet parts and is peened. However the pin 50 extends in the opposite direction and is arranged to engage the outer perimetral surface of the cam 44 as shown in Figs. 3 and 5. A bolt 51 is secured to the wall of the pulley 20 to support the trap spring 52 that has the bail 53 engaging the free end of the ratchet 47 forcing it inwardly to cause the pin 50 to strike the cam 44 or the tooth 54 of the ratchet to engage a tooth in the ratchet gear if the pulley is turned free of the stationary cam 44.

The ratchet being constructed of four or more pieces may be made up of stamping punched to provide the proper contour and with the holes to receive the pins 48 and 50 which when peened thereon secure the ratchet parts as a unit that can be readily hardened and assembled.

As the handle 26 is drawn outwardly the pull cord 25 rotates the pulley 20 in a clockwise direction in Figs. 1 and 5 and the pin 50 rides off the surface of the cam 44, permitting the bail 53 of the trap spring 52 to force the tooth 54 of the ratchet into engagement with a tooth of the ratchet gear 18. Further pull will permit the pull cord 25 to rotate the pulley 20 and the gear 18 with the crank shaft 14 for three fourths of a revolution when the pin 50 engages the abrupt rise 55 of the cam 44 and forces the ratchet out of engagement with the ratchet gear and the stop 56 on the pulley 20 engages the opposite face of

the stop 57 on the frame 24. Thus at the beginning and the end of the stroke the ratchet is held out of engagement with the ratchet gear. As the pull cord 25 is unwound the recoil spring 21 is wound up and when the handle is released the spring 21 returns the pulley 20 to the starting position as shown in Fig. 3 where the stop 56 on the pulley 20 engages the stop 57 on the frame 24. It should also be noted that the ratchet is in the same plane as the pull cord 25 and the guide pulleys 30 and 31 have deep grooves which permit them to be very close together and allow the handle 26 to be pulled at an angle to the throat formed by the grooves of the guide pulleys without affecting the proper application of force on the starting pulley 25.

The handle 58 of the gasoline hammer is provided with the throttle lever 59 pivoted substantially in the center of the handle 58 and extending in the direction of and beyond the recoil starter. Thus an operator stands the gas hammer on the tool, grasps the handle and gas throttle in the left hand directly above the recoil starter and pulls on the pull cord handle 26. Thus a direct pull will not twist the hammer out of the operator's grasp and he is enabled to start the tool without difficulty and has the throttle at hand to control the supply of gasoline fed to the hammer.

In the modified structure shown in Fig. 6 the shaft 14 has been shortened and has the hub member 60 secured thereto by means of the pin 61. The outer face of the hub member 60 is provided with a recessed chamber 62 having one or more pockets 63 for receiving the ball members 64. The crankcase 13 is provided with an extension 65 having an auxiliary disposed bearing 66 carrying the shaft 67. The inner end of the shaft is provided with an integral head 68 having one or more recesses 69 arranged to receive a portion of a selected ball member 64 to provide an overrunning clutch action therebetween. The outer end of the shaft 67 is arranged to receive the key washer 70 having a radial key section 71 engaging the corresponding slots in the cup-shaped plate 72. The sides of the end of the shaft 67 is provided with flattened key surfaces and the washer has an oblong hole arranged to snugly fit the same to prevent relative rotary motion therebetween. The washer 70 is secured to the shaft 67 by means of the screws 73 and is sufficiently large in diameter to hold the plate member 72 in assembled position and provide a driving connection between the plate and the shaft.

Adjacent its perimeter the plate 72 is provided with a series of openings for receiving the outer ends of the studs 74 which are formed on the flange 75 of the pulley 76. The pulley 76 is in turn journaled on the housing extension 65, making it free to rotate relative thereto. The pulley 76 is provided with a groove 77 arranged to receive several turns of the pull cord 78 which is secured at its inner end to the pulley 76 and is provided with a handle 79 at its outer end which extends through a tangentially disposed housing 80 on the extension 65. A helical flat spring 81 is secured at its inner end to the housing 65 by means of the pin 82 and at its outer end to one of the posts 74 on the pulley 76.

Thus when the handle 79 of the pull cord 78 is drawn away from the housing 65 one of the sockets 69 will receive a portion of the ball 64 when passing one of the pockets 63. Since the socket 69 is insufficient to fully retain the ball 64 the latter acts as a ratchet and causes the

hub 60 to be rotated with the shaft 67. This spring recoil starting mechanism is simple and economical in design and provides a ball ratchet member that lends itself to long life with little wear.

I claim:

In an internal combustion percussion hand tool comprising an engine with a crankshaft operated by a timing piston and having a working percussion piston, a starting mechanism mounted on the crankshaft and having a pull cord operatively connected to extend substantially horizontally and apply cranking forces in a plane lying transverse to the crankshaft when the tool is upright, and a guide handle attached to the engine and having a hand grasp mounted directly

in said plane to prevent twisting of the tool to provide control of the upright tool while cranking.
